UNITED STATES PATENT OFFICE

2,317,193

CHAIN LADDER

Harold P. Hopp, Englewood, N. J., and Edward Kunzelman, Mount Vernon, N. Y., assignors to H. K. Metal Craft Manufacturing Co., New York, N. Y.

Application June 26, 1942, Serial No. 448,550

6 Claims. (Cl. 228—40)

This invention relates to ladders and more particularly it relates to flexible ladders of the type used aboard ships.

It is one object of the invention to provide a novel construction whereby a ladder of the aforementioned type may be constructed entirely of metal without unduly increasing the weight over such ladders as generally constructed from rope and wood.

It is another object of the invention to provide a ladder which is possessed of a high degree of flexibility. Since such ladders are generally stowed in rolled form ready for use, this flexibility is a highly desirable feature, since it permits of rolling the ladder into a relatively smaller space than is possible with ladders constructed of rope and wood. A high degree of flexibility also permits of free and ready unrolling of the ladder when it is thrown over the side from its stowed position to its position for actual use.

It is still another object of the invention to provide a ladder in which damaged parts may be readily repaired or replaced when necessary.

A still further object of the invention resides in a structure in which, although comparatively light materials are employed, the ladder is possessed of sufficient strength to meet all conditions to which it may be subjected in normal use.

Flexible ladders of the general type above mentioned are usually of two types, namely, those used over the side of a ship, which type has ears at the ends of the rungs or steps and, that type for use in open hatches between decks and similar locations, which latter type has no spacing ears.

It is still a further object of the invention to provide a novel construction which is equally adaptable to ladders either with or without spacing ears.

With the foregoing objects in view, reference will now be had to the accompanying drawing, in which the invention is illustrated in connection with a ladder of the type which employs spacing ears and also with a ladder in which no spacing ears are employed.

In the drawing,

Figure 1 is a view in elevation partly broken away of a ladder of the type having no spacing ears, constructed in accordance with the present invention.

Figure 2 is a detail end elevation of one of the steps or rungs of the ladder,

Figure 3 is a detail horizontal sectional view on an enlarged scale taken substantially on the line 3—3 of Figure 1, and;

Figure 4 is a view similar to Figure 3 illustrat-

ing the invention as applied to a ladder of the type employing spacing ears.

Referring specifically to the drawing, the ladder consists of side members or stiles 10, to which are connected steps or rungs 11 which are rigidly attached to the stiles 10 in spaced relation to one another.

The stiles 10 are formed from continuous chains the links of which, in the present embodiment of the invention, are illustrated as of elongated loop form having two parallel side portions 12.

The rungs 11 are formed from sheet metal and are preferably of inverted channel cross-sectional form having a tread portion 13 and depending side flanges 14.

The side flanges 14 serve to strengthen the rungs and additional strength may be provided by forming upstanding beads or ribs 15 which extend along the side edges of the tread portions 20 of the rungs.

Each rung 11 has its ends rigidly secured to their respective stiles 10 by means which is received within the ends of the rungs which means, when in position, also serves to close the ends of the rungs.

This attaching means comprises, in each case, two U-shaped clips 16 and 17, each of which is preferably formed of sheet metal. The U-shaped clip 16 is of such a size that it may be passed into the open end of the rung 11 with the outer faces of its leg portions having engagement with the inner faces of the side flanges 14 of the rung. The U-shaped clip 17 is of a size to nest snugly within the clip 16 as illustrated in the drawing.

In securing the clips to the stiles, the two parallel portions 12 of one of the links is clamped between the two base portions 18 of the nested clips 16 and 17 by means of a rivet or the like, 19.

One of the clips, preferably the inner clip 17, is formed in its base portion 18 with two channels 20 properly spaced to receive the parallel side portions 12 of the link to which the clips are attached and the inner head 21 of the rivet 19 occupies a position between these channels 20.

The clips 16 and 17 are secured to the rung by means of rivets or the like, 22, which pass through the legs of the clips 16 and 17 and the depending side flanges 14 of the rung.

From the foregoing it will be apparent that the structure is one possessed of great strength since the clips serve to provide rigidity at the ends of the rungs and also serve as a closure means for the ends thereof. Strength between the ends of the rungs is provided by the ribs

or beads 15 which extend longitudinally of the side edges of the tread of the rung.

The construction results in a ladder having great strength and a high degree of flexibility by reason of the stiles being of link construction.

By reference to Figure 4 of the drawing, it will be apparent that the construction also readily lends itself to ladders in which spacing ears are employed.

In said figure, the spacing ears are designated 30. They are formed of metal having a straight portion 31 and two angular legs 32 which terminate in angular extensions 33 which engage the outer faces of their respective side flanges 14 of the rung 11. The straight portion 31 of the ear may be secured to the clips by the rivet 19 while each of the angular extensions 33, may be secured to their respective side flanges of the rung by one of the rivets 22.

Having thus described the invention, what it is desired to cover by Letters Patent is:

1. In a chain ladder in combination, a rung or step of inverted channel form and stiles in the form of link chains, and means for securing each end of the rung or step to its respective stile, said securing means comprising a pair of nested U-shaped clips for clamping one of the links of the stile, means for securing the clips in their link clamping position, and means for securing the clips to the side walls of the rung or step.

2. In a chain ladder in combination, a rung or step having a tread portion and side flanges depending therefrom and stiles in the form of link chains, and means for securing each end of the rung or step to its respective stile, said means comprising a pair of nested U-shaped clips, means for securing the clips to the stile, and means for securing the clips to the depending flanges of the rung or step.

3. In a chain ladder in combination, a rung or step of inverted channel form and stiles in the form of link chains, and means for securing each end of the rung or step to its respective stile, said means comprising a pair of nested U-shaped metal clips, means for securing the clips to the stile with a link of the stile clamped between the base portions of the clips to the side walls of the rung or step with the base portions 10 of the clips closing the end of the rung or step.

4. In a chain ladder in combination, a rung or step of inverted channel form and stiles in the form of link chains, and means for securing each end of the rung or step to its respective stile, said means comprising a pair of nested U-shaped metal clips, means for securing the clips to the stile, and means for securing the clips to the inner faces of the side walls of the rung or step to provide reinforcing means for said rung or step.

5. In a chain ladder in combination, a rung or step of inverted channel form and stiles in the form of link chains, and means for securing each end of the rung or step to its respective stile, said means comprising a pair of nested U-shaped metal clips, means for securing the clips to the stile with a link of the stile clamped between the base portions of the nested clips, and means for securing the nested clips to the rung or step with the leg portions disposed within the rung or step.

6. In a chain ladder in combination, a rung or step of inverted channel form and stiles in the form of link chains, and means for securing each end of the rung or step to its respective stile, said means comprising a pair of nested U-shaped clips, one of which has a pair of spaced grooves or channels formed in the base portion thereof.

HAROLD P. HOPP,
EDWARD KUNZELMAN.
